UNITED STATES PATENT OFFICE.

CORD H. BEHNKE, OF MASPETH, NEW YORK.

RADIATOR CAP.

Application filed October 30, 1924. Serial No. 746,731.

This invention relates to caps adapted to be attached to the neck of the radiator of an internal combustion engine, and is particularly useful in connection with the type of cap which has a body portion adapted to be permanently secured to the radiator neck, and a closing member, usually pivoted upon said body member, said closure member being adapted to support a motor heat indicator of a well-known type.

Radiator necks, to which caps of the style above mentioned are applied, are of various sizes and kinds; and it has been found in practice to be a difficult matter to insure the making of an absolutely water-tight connection between the radiator neck and the cap. At first thought, it would seem that such a water-tight connection could be obtained by providing a gasket, of rubber or some other yielding material, between the radiator neck and a shoulder within the cap. Experience has shown, however, that while such an arrangement may be satisfactory with some kinds of radiator necks when the caps are carefully installed thereon, it is often unsatisfactory, owing to the fact that the gasket may be squeezed out of its proper position during the installing operation, which results in a leaky instead of a tight joint.

The general object of the invention is to provide a new and improved means, adapted to cooperate with a radiator cap of the kind above mentioned, for insuring a non-leaking connection between the radiator neck and the cap. In attaining this object, the invention comprises certain means, adapted to cooperate with a gasket interposed between the cap and a radiator neck, for limiting the deformation of the gasket during the installing operation, thereby ensuring that the gasket will always perform its function in a reliable and satisfactory manner.

The invention will be understood from the following description, taken in connection with the accompanying drawing, in which Figures 1, 2 and 3 are elevations, partly in section, of a radiator cap having the invention embodied therein. Figure 1 shows the manner in which the invention cooperates with a well-known type of radiator neck having a thin wall and an in-turned flange; Figure 2 is applied to a radiator neck having a thin wall which presents a comparatively sharp edge; and Figure

3 shows the invention applied to a thick-walled radiator neck.

In all of the figures, the cap is shown as comprising a body portion 5, provided with oppositely extending arms 6, terminating in balls or symbol carriers 7; to which body portion is pivotally attached a cover 9 between which and the body portion is interposed a washer 10 of rubber or other yielding material. As shown, the body portion 5 is provided with an opening therethrough having a shoulder 12, and a threaded portion 13 adapted to cooperate with the threads on the outside of a radiator neck 14. Set screws 15 are shown extending through the lower portion of the body member 5 and into cooperative relationship with the threads on the radiator neck 14, for the purpose of locking the cap in any position to which it may be adjusted on the radiator neck.

In order to provide a water-tight joint between the radiator neck 14 and the cap, a gasket 16, of rubber or some other suitable yielding material, is arranged between the shoulder 12 and the top of the radiator neck 14. Cooperating with this gasket is a sleeve 18, preferably of thin metal, such as brass, which is in-turned at one end as shown at 19, and at the other end is provided with a flange 20. This sleeve 18 is preferably of such a size that it will engage the wall of the opening through the body member 5 above the shoulder 12, and will also engage the inside of the gasket 16, with the flange 20 of the sleeve in engagement with the outside of said gasket. In assembling the cap, the gasket 16 is first inserted in place adjacent the shoulder 12 and the sleeve 18 is then forced into the position just described.

The manner in which the gasket 16 and the sleeve 18 serve to make a water-tight joint between the cap and the radiator neck will be apparent from the drawing. With each form of radiator neck shown, the sleeve 18 effectively limits the internal deformation of the gasket 16 when the cap is screwed tightly on to the radiator neck. With the types of radiator necks shown in Figures 1 and 3, the top of the neck may engage both the gasket 16 and the flanged edge 20 of the sleeve 18; and with a neck of the type shown in Figure 2, the gasket only may be engaged by the upper edge of the neck. In each case, however, the gasket 16 is put under pressure between the upper end of the

neck 14 and the shoulder 12 in the body portion 5 of the cap, and the gasket is properly retained in position to seal the opening between these parts. Any tendency for the 5 gasket to be squeezed inwardly out of its proper position during the installing operation, is effectively resisted by the sleeve 18. Even if the cap is screwed down exceedingly hard on to the radiator neck, and is then un- 10 screwed somewhat in order to bring the arms 6 to the desired position, the gasket 16 will not be forced out of its proper position, but will continue to perform its function properly.

15 What I claim is:

1. A cap adapted to be attached to the neck of the radiator of an internal combustion engine, said cap being provided with a shouldered opening for receiving the radiator neck, a gasket cooperating with the shoulder in said opening, and an insert sleeve having a flanged edge engaging the margin of the bottom of the gasket and a body extending inside said gasket and held 20 in place by the basket, for limiting the internal deformation of the latter under pressure.
- 25 2. The combination with a radiator neck

of a radiator cap threaded thereon, said cap having a shoulder overlying the upper rim of the neck, a gasket seated against said shoulder to bear against the upper rim of the neck for sealing the joint between the cap and the neck, an insert sleeve lining the gasket and holding it in place, said sleeve comprising a flange extending beneath the inner margin of the gasket and resting upon a portion of the upper rim of the neck, and an upstanding body portion embraced and gripped by the gasket.

3. A cap adapted to be attached to the neck of a radiator of an internal combustion engine, said cap being provided with a shouldered opening for receiving the radiator neck, a gasket seated against the shoulder in said opening, and a thin metal sleeve in turned at one end and having a flange at the other end constructed and arranged to be forced into the gasket to position the flanged edge of the sleeve in engagement with the bottom of said gasket, and to be gripped and held in place by the gasket.

In testimony whereof I have affixed my signature to this specification:

CORD H. BEHNKE.
